DESIGN FOR A TRIMMING FOR WEARING-APPAREL.

58,576.

Specification for Design.

Patented Aug. 2, 1921.

Application filed May 20, 1921. Serial No. 471,243. Term of patent 3½ years.

To all whom it may concern:

Be it known that I, FRANK J. KEIL, a citizen of the United States, residing in the city, county, and State of New York, have invented a new, original, and ornamental Design for a Trimming for Wearing-Apparel, of which the following is a specification, reference being had to the accompanying drawing, forming part thereof, and in which—

Figure 1 is a fragmentary view of a piece of trimming for use with women's outer wearing apparel, showing my new design, the same indicating the petals of the rosette

as secured along their inner edges, loose at their outer, embroidered edges and lined with material different in color or texture, the same showing at the margin of the outer petals and other openings, the petals being cut directly from the outer material and disposed in the plane thereof.

Fig. 2 is a transverse sectional view of the same.

I claim:—

The ornamental design for a trimming for wearing apparel as shown.

FRANK J. KEIL.
